UNITED STATES PATENT OFFICE.

GEORGE BERRINGER, OF BLANCO, TEXAS.

COTTON-CHOPPER.

SPECIFICATION forming part of Letters Patent No. 691,102, dated January 14, 1902.

Application filed October 5, 1901. Serial No. 77,665. (No model.)

To all whom it may concern:

Be it known that I, GEORGE BERRINGER, a citizen of the United States, residing at Blanco, in the county of Blanco and State of Texas, have made certain new and useful Improvements in Cotton-Choppers, of which the following is a specification.

My invention is an improvement in that class of cotton-choppers in which a device in the nature of a hoe-blade is attached to a lever-arm adapted to swing or rotate in a vertical plane, whereby it chops out some of the standing cotton-plants as the machine advances, thus leaving the plants in bunches, as desired.

The construction, arrangement, and operation of parts are as hereinafter described, reference being had to the accompanying drawings, in which—

Figure 1 is mainly a side elevation of the machine, one of the transporting-wheels being removed and other parts broken away to show a portion of the mechanism. Fig. 2 is a front end view. Fig. 3 is mainly a rear end view, a portion being in section. Fig. 4 is a plan view.

The frame A of the machine is rectangular and mounted upon an axle B of transporting or running wheels C. The axle B and the front cross-bar *a* of the frame have an upward spring or arch, as shown in Figs. 2 and 3. The chopper or blade D is attached to a lever-arm E, which is pivoted and adapted to swing on the crank-arm F of a shaft G, which is journaled in pivoted swinging arms H. The said arms H are pivoted to the axle B and the front and rear bars *a* *a'* of the frame at points adjacent to the upward spring or arch before referred to. The free end of the lever-arm E projects through a keeper I, attached to one of the side bars of frame A, as shown. An antifriction-roller J is arranged in the lower side of said keeper I, and the lever-arm E bears and slides upon the same when the machine is in operation. The weight of the chopping device, the crank-arm F, and the shaft G serves to carry the latter down into the position required for efficient operation of the chopper D. Such position is illustrated in Fig. 2. Rotation is imparted to the shaft G and the required swinging movement

to the chopper D through the medium of gearing, which derives motion from one of the transporting-wheels C, as will now be described. A bevel-gear K is attached to the inner side of one of said wheels concentrically therewith. A shaft L, having on its rear end a bevel-pinion M, that meshes with the driving-gear K, is mounted horizontally in bearings between the wheel C and the side of the frame and projects at the front end of the latter, where it is provided with a sprocket-wheel N. A smaller sprocket-wheel O is keyed on the front end of the shaft G, and a chain P runs on the two sprockets, as shown. The said chain is slack when the shaft G is raised, as shown in full lines, Fig. 3, but is taut when the shaft is lowered to the working position shown in Fig. 2.

For the purpose of raising the shaft G and its attached chopper D to the position shown in full lines, Fig. 3, and holding it locked in such position I employ a hand-lever Q, which is pivoted to a bracket R, attached to the frame. As shown in Fig. 1, an arm of said lever Q is connected by links T with the shaft G, and it may be locked in any required adjustment by means of a spring-pawl U, which engages a notched segment V.

It will be seen that when the lever Q is adjusted properly the shaft G is lowered, and the sprocket-chain P being then taut rotation will be imparted to the shaft and the chopper D caused to swing in a circular arc, and in so doing it will remove at each rotation a portion of the growing cotton-plants. In other words, as the machine advances the movement of the chopper, due to the rotation of the shaft G and its crank-arm F, will have the effect of chopping out the cotton at intervals of spaces and leave the remainder standing in bunches, as required.

For the purpose of throwing the chopper out of action I provide the shaft L with a clutch W, which is adapted to slide thereon and is operated through the medium of a horizontal pivoted lever X and a vertical lever Z. The latter is pivoted like the lever Q, before described, and similarly provided with a spring locking-pawl, which engages a notched segment.

The operation is obvious. The frame A is

provided with a tongue or pole a^2 , which is rigidly attached to the central portion thereof, as shown.

As shown in Fig. 4, the shaft G is not continuous, but formed of aligned portions, which are rigidly connected by the crank F, this construction being necessary to enable the lever-arm E of the chopper to have the required reciprocating movement.

10. The machine is simple and inexpensive in construction. The chopper may be quickly lowered to be set in action and operates effectively with minimum friction.

What I claim is—

15. 1. The combination, with the wheeled frame and a series of swinging arms pivoted thereto, of a shaft mounted rotatably in the free ends of said arms and provided with a crank as described; a chopper proper having a lever-arm hinged upon said crank; means for raising the said shaft with its attached chopper, and means for imparting rotation thereto; substantially as shown and described.

25. 2. The combination, with the wheeled frame and arms pivoted thereto and adapted to swing in a vertical plane, of a shaft journaled in the free ends of said arms and provided with a crank; a chopper having a lever-arm hinged on said crank; a keeper arranged on 30 the frame, the said lever-arm working in the same; and means for rotating the said shaft; substantially as shown and described.

35. 3. The combination, with the wheeled frame having an axle and cross-bar each provided with an upward spring or arch, of a crank-shaft passing beneath said arches, swinging arms in which the shaft is mounted, a chopper attached to the crank of said shaft, and means for rotating and raising said shaft, substantially as shown and described.

40. 4. The combination, with the wheeled frame and arms pivoted thereto so as to swing in a vertical plane of a rotatable shaft journaled in said arms and formed in sections, which 45 are aligned; a crank-arm which rigidly connects the said sections and is provided with an open slot as shown; a chopper having a lever-arm which is hinged on said crank; a keeper fixed on the frame and through which

the chopper-arm reciprocates; and means for raising the said shaft and chopper in the manner described.

5. The combination, with the wheeled frame and arms pivoted thereto so as to swing in a vertical plane, a rotatable crank-shaft journaled in said arms, and a chopper attached to the crank of said shaft, of a lever pivoted upon the frame and provided with means for locking it in different adjustments, and a link connection between said lever and shaft, substantially as shown and described.

6. The combination, with the wheeled frame and arms pivoted thereto and swinging in a vertical plane, of a rotatable crank-shaft journaled in said arms and having a sprocket-wheel affixed to one end thereof, a bevel-gear attached concentrically to one of the transporting wheels; a shaft geared therewith and having a sprocket-wheel on its front end; a chain running on said sprocket-wheels; a 70 chopper attached to the crank-shaft; and lever-and-link mechanism for raising said shaft, the arrangement being such as described, whereby, when the shaft is lowered to carry the chopper into position for operation, the 75 sprocket-chain is taut, substantially as shown and described.

7. The combination, with the wheeled frame having an axle and cross-bars each provided with an upward arch, of arms pivoted and swinging in a vertical plane, the rotatable shaft journaled in said arms and provided with a crank having an open slot, a chopper attached to a lever-arm, the latter being hinged upon the crank and working in a 85 keeper fixed on the frame; a lever-and-link mechanism connected with the shaft, whereby it may be swung up into the aforesaid arches; a driving-shaft geared with one of the transporting-wheels; sprocket-wheels affixed to the aforesaid shafts; and a chain running on such sprocket-wheels; all as shown and described.

90 GEORGE BERRINGER.
